UNITED STATES PATENT OFFICE.

ALEXANDER BOUCHER AND THOMAS JOHN McCLOSKEY, OF NEW YORK, N. Y.

SMOKE AND GAS EJECTOR FOR ORDNANCE.

SPECIFICATION forming part of Letters Patent No. 759,803, dated May 10, 1904.

Application filed February 8, 1904. Serial No. 192,512. (No model.)

To all whom it may concern:

Be it known that we, ALEXANDER BOUCHER, whose residence and post-office address is 178 DeKalb avenue, and THOMAS JOHN McCLOSKEY, whose residence and post-office address is 420 Halsey street, Brooklyn, county of Kings, State of New York, citizens of the United States, have invented certain new and useful Improvements in Smoke and Gas Ejectors for Ordnance, fully described and represented in the following specification and the accompanying drawings, forming a part of the same.

It is well known that when heavy guns are fired and the breech opened soon afterward to insert a new charge the smoke and gases generated by the explosion escape from the breech-opening and cause great injury to the gun crew by their ignition or by their poisonous character. This is especially the case with large guns on shipboard, as such guns are often fired while the ship is in motion and with the muzzle pointed to the bow of the vessel, so that the movement forces a strong draft into the bore of the gun when the charge is not actually escaping. The evils which result from such escape of gases and smoke are felt most severely with turret-guns, as the crew of such guns are confined in a small space, where there is but little opportunity for ventilation or for avoiding the breech of the gun when the breech-block is opened, and very serious injury has often been suffered by such turret crews from such cause. It has heretofore been attempted to prevent such discharge of smoke and gases from the gun-breech by operating upon the bore of the gun at the breech; but the present invention wholly avoids the necessity of any breech attachments, as it operates at the muzzle of the gun.

The invention consists of a fixture attached to the muzzle of a gun and supplied with fluid under pressure, the fixture discharging a jet or jets of fluid directed forwardly from the muzzle by the fixture around the axis of the gun, so as to produce a strong forward current from the mouth of the bore, which sucks the contents of the bore therefrom. This ap-

pliance operates by the same law as has long been used in the construction of ejectors of various kinds—namely, the law that a forwardly-moving current of fluid tends to carry with it any body of fluid adjacent thereto.

The nature and operation of the invention will be understood by reference to the annexed drawings, in which—

Figure 1 is a longitudinal section of an eight-inch gun, drawn upon a small scale, with the breech-block partly retracted and the fluid jet operating at the mouth of the gun to discharge the contents of the bore forwardly. Fig. 2 is a side view of the muzzle with the jet-fixture in section at the upper edge of the same. Fig. 3 is a front view of the muzzle with the jet-fixture. Fig. 4 is a side view of the base-plate for the sectional jet-fixture, and Fig. 5 is an edge view of the same. Fig. 6 shows the muzzle of the gun in section with a jet-fixture movable into and out of the muzzle. Fig. 7 is a longitudinal section, upon a larger scale, of the chambered block *a* shown in Fig. 6; and Fig. 8 shows the front end of such chambered block.

a designates the body of the gun, *b* the bore, and *c* the breech-block. An annular metallic shell *d* is shown surrounding the gun-muzzle and formed with an annular chamber which is open at the forward edge in a narrow slit which forms a nozzle *e*, inclined to the axis of the bore to project an annular jet forward in conical shape, as indicated by the lines *f* in Fig. 2. The annular shell is provided with an inlet *g* to supply the chamber and with a pipe *h*, connected to a flexible hose *i*, which is able to bend freely when the gun recoils. A cock *j* is shown in the pipe *h* to set the jet in operation when desired.

Fig. 2 shows a convenient construction to form the annular chamber within the shell by using a base-ring *k*, which furnishes the inner lip of the nozzle *e*, and a cover-ring *l*, secured to the base-ring by lugs *m* and adapted to form the body of the chamber and the outer lip of the nozzle. The outer ring is in practice divided to apply it to the inner ring, and the lugs are secured thereto by screws *n*, and

the base-ring is shown secured to the gun by screws *o*.

The ring *l* is shown formed with an inlet *g*, through which a pipe *h* delivers the fluid under pressure to the annular-chamber. It may be necessary in adapting the base-plate *k* to a flaring muzzle, as shown in Fig. 2 of the drawings, to make such base-ring in halves, and such a base-ring is shown in side view in Fig. 4 and in edge view in Fig. 5, with bosses *r* projected from it, upon which the half-sections of the ring *l* can be secured by the screws indicated at *s* in Fig. 5.

Figs. 6, 7, and 8 show a construction by which the jet-fixture may be operated within the muzzle of the gun immediately after firing. The fixture consists of a chambered block *u*, connected by a pipe *h'*, with a hollow journal *h''* mounted in a bearing *u'* and provided with a handle *v*, by which the fixture can be moved in and out of the muzzle, as indicated by the dotted lines *u'*. The hollow journal can be supplied with fluid under pressure by any kind of swiveling joint, such as are often used for a movable connection. The block *u* has a circular series of jet-apertures *e'*, adapted to throw jets *e''* forward within the muzzle, as shown in Fig. 6, thus producing a forward movement of the smoke and gases in the bore. The rear end of the block is pointed to facilitate the movement of the gases past the same. A single jet propelled forward in the muzzle of the gun would obviously produce the same effect, but could not be so readily supported by a movable pipe as the block shown, which is connected with the pipe by a central aperture and can readily be furnished with jet-openings surrounding the center.

Heavy ordnance is often fired with great rapidity, and it is well known that under such conditions the poisonous and explosive gases escape from the breech of the gun as soon as the gas-check is loosened. By operating the jet-fixture before loosening the gas-check a forward movement is initiated in the bore, so that as soon as the gas-check is loosened and the movement of the breech-block is commenced air begins to enter at the crevices and discharges the contents of the bore before the breech-block is fully opened. Such influx of cool air not only relieves the gun crew from injury, but serves to cool the bore of the gun materially.

In modern warships it is common to supply water under pressure for washing out the bore of the gun at intervals, and no special equipment is required to operate the jet-fixture, as a simple connection of the pipe *i* to

such water-supply suffices to make the fixture 60 operative.

In Fig. 1 of the drawings, the jet is shown inclined very slightly, while in Fig. 2 the jet is directed inwardly at an angle of forty-five degrees with the axis of the bore. 65

Two constructions are shown to illustrate the various ways in which the invention may be practiced, as both produce the same effect upon the bore of the gun.

It is immaterial whether the jet be discharged from an annular nozzle or from a series of pipes or jet-apertures, as the effect is the same, and the invention is not, therefore, limited to any particular construction or inclination of the jet-nozzle. 70

In Fig. 1 the gases (indicated by the shading) are shown already cleaned from the combustion-chamber of the gun, the current of air entering at the breech being indicated by arrows *t*. 80

Having thus set forth the nature of the invention, what is claimed herein is—

1. The means for drawing the smoke and gases from a gun-bore, which consists of a jet directed forwardly at the muzzle to produce 85 a partial vacuum within the bore.

2. The combination, with a gun, of a jet-fixture attached to the muzzle, and means for supplying fluid under pressure thereto, operated to produce a partial vacuum within the 90 gun-bore.

3. The combination, with a gun, of an annular jet-fixture attached to the muzzle, and means for supplying fluid under pressure thereto, the whole operated to produce a forwardly-directed jet around the muzzle of the gun, to draw the smoke and gases from the 95 bore.

4. A jet-fixture for the muzzle of a gun, comprising the annular base-plate and the annular cover-plate secured together with intermediate chamber, and narrow aperture at the side, the chamber being provided with an inlet and pipe to supply fluid under pressure. 100

5. A jet-fixture for the muzzle of a gun, 105 comprising the annular metallic shell having annular chamber therein with narrow annular aperture at one side, and the shell being provided with an inlet for supplying fluid to the chamber. 110

In testimony whereof we have hereunto set our hands in the presence of two subscribing witnesses.
